UNITED STATES PATENT OFFICE.

JOHN O'CONNELL, OF PROVIDENCE, RHODE ISLAND.

AUTOMATIC ALARM FOR FRICTION-BEARINGS.

SPECIFICATION forming part of Letters Patent No. 308,192, dated November 18, 1884.

Application filed May 26, 1884. (No model.)

To all whom it may concern:

Be it known that I, JOHN O'CONNELL, of Providence, in the county of Providence and State of Rhode Island, have invented a new 5 and Improved Automatic Alarm for Friction-Bearings, of which the following is a full, clear, and exact description.

The object of my invention is to provide for giving an alarm or signal when the bearings of shafting or parts of machinery become overheated by friction.

The invention consists in the construction and combination of parts, as will be herein-after fully described and claimed.

15 The drawings represent two modes of carrying out the invention, and by the use of bell or gong signals.

Figure 1 shows the improvement applied to the journal-box of a power-transmitting shaft, 20 and Fig. 2 shows its application to the crank-pin bearing of a steam-engine.

Referring, first, to Fig. 1 of the drawings, A is a power-transmitting shaft, and B its journal box or bearing. C is the fusible head, 25 which is attached to the end of a wire, D, which connects suitably at d with a lever, E, fulcrumed at e on a post, F, fastened to the box B. The lever is bent downward at g to form an arm, G, to which the bell H is connected, as shown, and the end of arm G carries, or may carry, a foot-piece, i, which may be struck by any suitable stud or tappet, I, fixed on the shaft A, when the bearing becomes hot enough to melt the fusible head C. The 30 head C is held in contact with the bearing B by confinement beneath a bridge piece or plate, c, fixed to the bearing, through which plate c the wire D loosely passes. It is evident that when the head C melts the superior weight of 35 the bell H will carry the arm G of lever E down to the shaft A, and the stud I will strike the arm to ring the bell at every revolution of the shaft.

Referring now to Fig. 2, J is the crank-disk 45 of a steam-engine, and K the wrist-pin on which the connecting-rod L is fitted by its brasses l. M is an arm, fitted at one end into the end of the wrist-pin K, and carrying at its other end the gong-bell N, which is shown 50 as having two oppositely-arranged tongues or clappers, O O, loosely connected with the arm

M at m, and connecting by wires P P with the fusible plugs R R, fitted snugly into the end bores, S S, of the wrist-pin K, and so as to hold the clappers O O out of contact with 55 the gong N until the overheating of the bearing-surface of the wrist-pin melts the plug R and permits the clapper O to be thrown outward by centrifugal force to sound the gong-bell and give the alarm. But one fusible plug 60 R, wire P, and clapper O need be used, if preferred.

I do not limit myself to the precise modes shown of setting the fusible heads or plugs in place, as they may be located in any way so 65 as to receive the heat from the friction-surfaces. My improvement may also be applied to give an alarm by the overheating of reciprocating or sliding surfaces, as will readily be understood.

70 The wire connections to the fusible head or plug may be arranged with suitable actuating mechanism or electrical devices to give a variety of signals to notify the engineer or attendants of the overheating of friction-surfaces in time to prevent serious damage to the machinery.

Having thus described my invention, what I claim as new, and desire to secure by Letters Patent, is—

1. The combination, with a journal-bearing and its journal, of a fusible material adapted to be fused by undue heat of said parts, and connected to an alarm, said alarm being constructed to be operated directly by the journal upon the fusing of the plug, substantially as shown and described.

2. The combination, with a shaft-journal bearing, of a fusible head retained on the bearing, and a bell-carrying lever connected with the 90 fusible head and arranged to be struck by a tappet on the shaft when the fusible head melts, substantially as described.

3. The combination, with the wrist-pin of an engine, of a bell supported thereon, and 95 fusible plugs held in the wrist-pin and connected by wires to the clappers of the bell, substantially as described.

4. The combination, with the journal-bearing B and the bridge c, secured thereto, of 100 the pivoted lever E, connected at its inner end with the bridge c by a fusible head, C, and

provided on its outer end with an arm, G, connected with an alarm mechanism, and adapted to be operated by a projection on the journal to cause said arm to sound said alarm upon the fusing of the head, substantially as set forth.

5. The combination, with the journal-bearing B and the bridge c, secured thereto, of the lever E, pivoted to standard F, and connected to with the bridge by a link, D, and fusible head,

and arm G, provided with the projection i and alarm-bell H, said projection i being constructed to be struck by the tappet I on the journal upon the fusing of the head, substantially as shown and described.

JOHN O'CONNELL.
